INVENTOR
JOHN B. HOAGLAND
By Edward S. Longman
ATTY.

UNITED STATES PATENT OFFICE.

JOHN B. HOAGLAND, OF ST. LOUIS, MISSOURI.

TAMPER FOR TOBACCO PIPES.

Application filed January 30, 1922. Serial No. 532,732.

To all whom it may concern:

Be it known that I, JOHN B. HOAGLAND, a citizen of the United States, and resident of the city of St. Louis and State of Missouri, have invented certain new and useful Improvements in Tamers for Tobacco Pipes, of which the following is a specification containing a full, clear, and exact description, reference being had to the accompanying drawings, forming a part hereof.

My invention relates to improvements in tampers for tobacco pipes, and has for its primary object a device for such purposes which may be used especially for advertising purposes for different brands of smoking tobacco.

In the drawings—

Fig. 1 is a plan view of a strip of sheet metal, stamped out and ready to be formed.

Fig. 2 a top plan view of my improved tamp when formed.

Fig. 3 an edge view of the same when partly formed.

Fig. 4 a similar view illustrating the device before the stem is finally folded.

Fig. 5 an edge view of the completed device.

Fig. 6 a side view of the same.

Referring to the drawings—

7 indicates a strip of sheet metal or the blank out of which my improved tamping device is formed. This blank consists of a hexagonal portion 8 which forms the head of the tampering device. 9 indicates strips which are formed integral with the head 8 and which are adapted to be folded over the head 8, as illustrated in Figs. 3, 4, and 5.

10 indicates the portions which are folded against the hexagonal head portion 8. After the portions 10 have been folded against the hexagonal portion 8, the remainder of the strips are folded against each other, as illustrated in Figs. 3, 4, and 5, so as to form an integral stem for the tamping device.

In Fig. 3 I have illustrated the same formed before the end of the stem is folded, in which it will be observed that one of the portions 9 is longer than the other portion so that when the end is folded over as illustrated in Fig. 4, the folded over ends of the

strips will occupy the same plane or be flush.

In Fig. 5 I have illustrated the final folding of the end of the stem which is really a double fold. By this final folding the ends of the strips 9 are securely united together, which forms on the stem an enlargement or shoulder which has a tendency to prevent the tamping device from slipping out of the fingers while it is being used.

In Fig. 6 I have shown the device with the name of the tobacco thereon.

My device is preferably stamped from sheet metal, but of course, may be made out of other materials. When formed out of sheet metal as shown and described, the edges may be used to scrape out the encrustation on the inner surface of the bowl.

Having fully described my invention, what I claim is:

1. A tamping device for smoking pipes, comprising a head portion, strips formed integral with said head portion at opposite edges thereof and of less width than the head portion, one of said strips being longer than the other, both of said strips adapted to be folded back upon the face of the head portion to a point approximately its center, the remaining portion of each strip adapted to be bent at right angles to the folded portion and to the head portion for forming a handle, the free ends of said strips adapted to be folded upon each other for preventing the strips from separating.

2. A tamping device for smoking pipes, comprising a strip of metal having an enlarged portion formed integral therewith and to one side of its center so that the portion of the strip on one side of the enlargement is longer than the other portion, each of said strips being so bent that a portion thereof will lie close to the surface of the enlargement and on the same side thereof, the remainder of said portions extending at right angles to said enlargement and contacting with each other, the free ends of said portions being folded upon each other whereby the same are prevented from spreading and a handle is formed.

In testimony whereof, I have signed my name to this specification.

JOHN B. HOAGLAND
